UNITED STATES PATENT OFFICE.

WILLIAM A. PAULUS, OF RIDGEWOOD, NEW JERSEY.

PACKAGE-BAND-FASTENING DEVICE.

1,092,855.

Specification of Letters Patent. Patented Apr. 14, 1914.

Application filed November 28, 1913. Serial No. 803,433.

To all whom it may concern:

Be it known that I, WILLIAM A. PAULUS, a citizen of the United States, and residing at Ridgewood, in the county of Bergen and State of New Jersey, have invented certain new and useful Improvements in Package-Band-Fastening Devices, of which the following is a specification, such as will enable those skilled in the art to which it 5 pertains to make and use the same.

This invention relates to fastening devices designed for use in securing packages of various articles of merchandise, such as gloves, neck ties, stockings, and like articles, and the object thereof is to provide an improved device of this class which is simple in construction, convenient in operation, and which will permit of the use of a flexible band or bands of paper or similar material without the necessity of tying the same.

The invention described and claimed herein is an improvement on that described and claimed in U. S. Letters Patent No. 1,021,884, granted to me April 2, 1912, and said invention is fully disclosed in the following specification of which the accompanying drawing forms a part, in which the separate parts of my improvement are designated by suitable reference characters in each of the 20 views, and in which;—

Figure 1 is a plan view showing my improved fastening device and indicating the method of its use in securing a package of gloves together;—Fig. 2 a plan view of a blank from which one part of my improved fastening device is made;—Fig. 3 a partial section on the line 3—3 of Fig. 1;—Fig. 4 a view showing one step in the process of forming my improved fastening device, and Fig. 5 a section on the line 40 5—5 of Fig. 1, and on an enlarged scale.

In the practice of my invention, I provide a band *a*, preferably of stiff paper or other fibrous material, and which for the purpose 45 of this description will be called a lock band, and this band is divided transversely by score or similar lines *a*² into four parts *a*³, *a*⁴, *a*⁵ and *a*⁶. The parts *a*³, *a*⁴ and *a*⁵ are approximately of the same dimensions 50 longitudinally and transversely, except that the side edges of the part *a*⁵ are made concave, as shown at *a*⁷, while the part *a*⁶ is triangular in form and preferably shorter than the other parts.

55 The lock band *a* is folded to form the lock member of my improved fastening de-

vice which is shown at *b*, and in this operation, the part *a*³ is first folded onto the part *a*⁴, and the parts *a*³ and *a*⁴ are then folded onto the part *a*⁵, after which the part *a*⁶ is folded over the part *a*⁴. I also employ, as a part of my improved fastening device, a tie band *c* composed of paper or other suitable fibrous material, and in practice, the end portion *c*² of said tie band is passed through the center of the lock member *b*, as shown at *c*³, and around and across the back thereof, as shown at *c*⁴, and is sealed to said back which consists of the part *a*⁶ and a corresponding triangular portion *a*⁸ of the part *a*⁴, as shown at *c*⁵. In this operation, I preferably provide one side of the part *a*⁶ with a suitable glue, mucilage or adhesive material *a*⁹ adapted to be moistened in the usual manner, and the corresponding side *a*⁸ of the part *a*⁴ of the lock band is similarly provided, as shown at *a*¹⁰, and when the end portion *c*² is passed through the lock member, as described, all that is necessary is to moisten the glued surfaces of the part *a*⁶ and corresponding portion of the part *a*⁴ and press the end portion *c*² of the tie band *c* thereonto. It will be understood, however, that while I prefer the above described process of procedure 70 which involves the application of glue, mucilage, or similar substance, to one side of the part *a*⁶ and to the corresponding side of the corresponding part of the part *a*⁴ of the lock band, this method of procedure is 75 not absolutely necessary, and instead thereof, the end portion *c*² of the tie band may be provided on one side with glue, mucilage or like substance, and when said end portion of the tie band has been passed through 80 the lock member *b*, the surface thereof provided with glue may be moistened and then sealed to the back of said lock member consisting of the part *a*⁶ of the lock band, and the part *a*⁸ of the part *a*⁴ thereof.

The package holder or fastening device is now ready for use, and in this use the end portion *c*⁶ of the tie band *c* is passed around the package and through the lock member, as shown at *c*⁷, and then passed back through 100 the lock member *b* and under the front part or fold *a*⁵ thereof. This forms a simple and effective fastening device for the bundle or package *d*, and one which is comparatively inexpensive, and when it is desired to 105 untie the bundle or package, the tie band may simply torn off, or the end portion *c*⁶ there-

of may be passed back from under the part a^5 of the lock member, and then pulled out in the direction of the arrow X of Fig. 3.

The free end c^8 of the tie band c is rounded, as shown in Fig. 1, to facilitate the passage thereof through the lock member b , as hereinbefore described, and the opposite side edges a^7 of the part a^5 of the lock band or lock member are made concave for a similar purpose, and the part a^5 of the lock member b , or lock band a , forms, as will be seen, a name plate, or face plate, on which the name of the manufacturer, or a trade mark, may be placed if desired, as shown at e in Fig. 1.

From the foregoing description, it will be seen that the main point of difference between the invention described and claimed herein, and that which is covered by the patent hereinbefore referred to, consists in cutting off the part a^6 of the lock band so as to make it triangular in form, whereby, when said part a^6 is folded over the part a^4 , a corresponding portion of the part a^4 will be left uncovered, and the end portion c^2 of the tie band may be sealed to both of said parts, and this results in, not only securing the end portion c^2 of the tie band to the lock member formed by the lock band a , but also secures the lock band in a folded position, or in other words, holds the lock member b formed from the lock band, in proper position and condition for use, and this facilitates the use of the fastening device, or the manipulation thereof for the purpose or purposes for which it is intended, and although I have described the part a^6 of the lock band as made triangular in form, it will be understood that this shape of said part is not an essential feature, all that is necessary in this connection being that said part a^6 of the lock band shall be smaller or less in dimensions than the part a^4 , in order that the end portion c^2 of the tie band may be sealed to both of said parts.

It will also be understood that while I have stated that the part a^6 , and a part of the part a^4 of the lock band, or the part c^2 of the tie band are, or may be provided with mucilage, gum, glue, or similar substance, in the making of said parts, for the purpose of sealing or securing said part c^2 of the tie band to the parts a^6 and a^4 of the lock band, this method of procedure is not absolutely necessary, as liquid glue or paste of any kind may be applied to the part c^2 of the tie band, or to the parts a^6 and a^4 of the lock band, after said members have been con-

nected, as shown in Fig. 4, and said part c^2 of the tie band may be folded over and secured to the parts a^6 and a^4 of the lock band, as will be readily understood.

Having fully described my invention what I claim as new and desire to secure by Letters Patent is:—

1. A fastening device consisting of a lock band composed of a strip of flexible material divided, by folding lines, into four parts, one end part being triangular in form and the other parts being substantially equal in dimensions, and said parts being folded to form a lock member and so that the triangular end part will lie on the part adjacent to the other end part, and a tie band passed through the folded lock band and one end of which is adapted to be sealed to the triangular end portion of the lock band, and that other portion of the lock band on which the triangular end portion rests, the other end of the tie band being free, and said folded lock band being adapted to permit the passage of the free end of the tie band centrally therethrough and between the folds of the same and under the front part thereof, the other end of said tie band being also rounded, and the side edges of the front face portion of the lock member being concave.

2. A fastening device consisting of a lock band composed of a strip of flexible material divided by folding lines into four parts three of which are approximately of the same dimensions, one end part being of less dimensions, and said parts being folded to form a lock member and so that the smaller end part will lie on the part adjacent to the other end part, and a tie band passed through the folded lock band and one end of which is adapted to be sealed to the smaller end portion of the lock band, and that other portion of the lock band on which the smaller end portion rests, the other end of the tie band being free, and said folded lock band being adapted to permit the passage of the free end of the tie band centrally therethrough and between the folds of the same and under the front part thereof, substantially as shown and described.

In testimony that I claim the foregoing as my invention I have signed my name in presence of the subscribing witnesses this 25th day of November 1913.

WILLIAM A. PAULUS.
